UNITED STATES PATENT OFFICE.

WILLIAM R. LANDFEAR, OF BROOKLYN, AND JAMES A. KEYES, OF NEW YORK,
N. Y., ASSIGNORS TO RICHARD H. WRIGHT, OF NEW YORK, N. Y.

MECHANISM FOR SEPARATING AND FEEDING SHEETS OF PAPER OR SIMILAR MATERIAL.

SPECIFICATION forming part of Letters Patent No. 683,858, dated October 1, 1901.

Application filed March 19, 1901. Serial No. 51,819. (No model.)

To all whom it may concern:

Be it known that we, WILLIAM R. LANDFEAR and JAMES A. KEYES, citizens of the United States, residing in the city of New York, in the State of New York, (the post-office address of the former being No. 258 Madison street, Brooklyn, and that of the latter being No. 550 East One Hundred and Sixty-third street, New York city, New York,) have invented new and useful Improvements in Mechanism for Separating and Feeding Sheets of Paper or Similar Material, of which the following is a specification.

The present invention relates to mechanism or devices for separating and feeding individual sheets of paper or similar material from a pile of superimposed sheets for delivery to printing, folding, wrapping, or labeling machines or for other uses to which such sheets are adapted.

Many devices have been designed and used to hold in place the sheets which are contiguous to one of the outer sheets of a pile, while such outer sheet (either at the top or bottom of the pile) is started and separated from the next sheet and is fed forward. One of the devices which has been used for this purpose is a needle or pointed blade arranged at the rear of the pile and operated to pierce the outer and one or more of the contiguous sheets, and as the outer sheet is fed forward or away from the rear end of the pile by a starting and feeding device arranged to operate directly upon this sheet the pointed device cuts or tears out a short slit or opening at the end edge of the sheet, while it holds the next sheets, which are subjected to less feeding force, in their normal positions in the pile. Heretofore this pointed device has been rigidly fixed to some stationary part of the mechanism, as the wall of the box which contains the pile of sheets, so as to pierce the uppermost sheets of the pile, and the piercing of the point into the sheets has been effected by the upward pressure of the pile against it, the pile being supported upon a movable platform, which is forced upward by an expansion-spring or other suitable automatic lifting device to exert a continuous and constant pressure against the piercing-point. A defect in the practical operation of

this device is that the piercing-point catches and holds fine fibers of the paper not only on its extreme end, but especially where it cuts or tears out the slit at the end of the upper sheet, and inasmuch as the continuous pressure of the pile against the point prevents any clearance from the accumulation of fibers the point soon becomes so clogged and shielded that it will not pierce the desired number of sheets, and if the operation is continued for any considerable period the second and sometimes even the top sheet will not be pierced and the device becomes unreliable to hold the under sheets in place while the outer or top sheet is started and fed.

It is the object of this invention to remedy the defect referred to by providing means by which the piercing-point is intermittently relieved from the continuous and constant pressure against the sheets and is cleared from any attached fibers, so that under ordinary conditions it will pierce a uniform number of sheets of a given thickness; and to this end the invention consists, generally stated, in means or devices by which a positive movement of sufficient range and force is given to the point to cause it to pierce the desired number of sheets. Preferably this movement is a sudden thrust and is intermittent or repeated for every sheet from the pile or often enough to keep the point free and clear of fibers; also in means by which the sheets, especially their rear ends, are permitted to move toward the piercing-point during the intervals between its thrusts and by which they are subjected to a vibratory or shaking movement caused by the action of the intermittent thrusts of the piercing-point on one side of the pile and the spring-controlled platform on the opposite side thereof.

A form of mechanism embodying the present invention is illustrated in the accompanying drawings, in which—

Figure 1 is a side or front elevation of the mechanism, the front part of the sheet-box being removed to show the movable platform and other parts. Fig. 2 is a plan view of the same. Fig. 3 is a front elevation of the rear part of the mechanism, showing the piercing-point and its operative devices in different positions from those seen in Fig. 1. Figs. 4

and 5 are side elevations of a modified construction, the two figures showing certain parts in different positions.

In the drawings, A represents a box or receptacle fixed to any suitable frame or support, in which a pile of sheets B is placed and from which the sheets are separated and fed one by one. The arrangement of the mechanism shown in the drawings is for feeding the sheets from the top of the pile by means of starting and feeding rollers C and C', located above the pile and fixed to their respective shafts c c', which are journaled in the bearings d d' to the frame or other fixed part of the mechanism and arranged to rotate in contact with the top sheet thereof, and a pair of drawing-rollers D D, located in the front of the forward end of the box A. The pile of sheets is supported by a platform E, arranged to move up and down within the box A, and constantly forced upward by an expansion-spring F to bring the top sheet of the pile into feeding contact with the rollers C and C'.

H represents a needle or other pointed device (hereinafter called the "piercing-point") adapted to pierce or puncture several sheets of the pile. This device is fixed, preferably adjustably, by screws h in a rock-arm I, which is pivotally secured to a stud J, fixed to a bracket J', projecting from the rear wall of the box A, or fastened to some other part of the mechanism, so that the piercing-point is free to be moved toward and away from the top of the pile. A positive movement toward the pile is given to the piercing-point by any suitable means, conveniently by its connection with a rotating cam K through the free end of arm I, with which the cam contacts to rock the arm downward and force the piercing-point into the upper sheets of the pile. The cam is preferably attached to and rotated with shaft c of roller C for reasons hereinafter set forth and is so shaped as to give the piercing-point a positive and intermittent thrusting movement into the sheets. The starting and feeding rollers C and C' have sections L on their cylindrical surfaces, preferably about one-half thereof, roughened or covered with sandpaper, rubber, or other suitable material to give them the requisite frictional contact with the outer sheet to start and feed it forward, while the rest of their surfaces are left smooth. The feeding-surfaces L are preferably so arranged relatively to the cam K, which gives the downward thrusts to the piercing-point, that the point will be in its lowest position when the smooth surfaces of the rollers are in contact with the sheets, for the reason that the extreme downward or home thrusts of the point force the platform E against the upward stress of the spring F and relieve the pressure of the top sheet against the smooth surfaces of the rollers, thereby lessening the liability of starting the next sheet of the pile before the top one has been fed therefrom and enabling the successive top sheets to be drawn forward

easily by the rollers D D or other devices at a greater speed than the surface speed of the starting-rollers C and C'. The downward movement of the platform under the successive thrusts of the piercing-point H are responded to by the resiliency of the contracted spring F, and a series of short quick vibrations is given to the pile which are resisted from above by the piercing-point.

It is desirable in order that the successive sheets may be seized by the rollers D D or other drawing devices at regular intervals to arrange a removable stop at the rear of such drawing devices against which the ends of the sheets impinge and are stopped as they are fed forward by the rollers C and C', which will cause the sheets to be buckled up between the roller C' and such stop, as shown in dotted line in Fig. 1, and when the stop is removed from the path of the sheets their upward ends will spring into the bite of the rollers D D. A convenient construction and arrangement of such stop and devices for operating it are shown in Fig. 1 of the drawings, in which the stop consists of a series of pins M, fixed to a shaft N, journaled in brackets fixed to the front of the box A and held in its normal position, so that the pins will be out of the path of the sheets, by spring O, having one of its ends secured to the pin P on the shaft and its other end to some fixed point, as hook Q, and is rocked backward to bring the pins into the path of the sheets by a connecting-arm R, whose forward end is pivoted to the crank-arm S, fast to the rock-shaft N, and its rear end is yoked over the shaft c' of roller C', the arm R being reciprocated to rock the shaft N by the engagement of a rotating cam T, fixed to shaft c', with a pin-supported roller U on the arm R. The lower drawing-roller and the forward end of bridge e are preferably provided with grooves to receive the pins M when they are in and out of their stopping positions.

The rollers C and C' may be driven by any means which will cause them to rotate at the same peripheral speed, conveniently by connecting them by a chain W, passing over sprocket-wheels fixed to their respective shafts, and by positively rotating the roller C by means of a chain V, passing over a sprocket-wheel on its shaft and over any other properly-driven wheel. (Not shown in the drawings.)

It is observed that in the construction thus far described and shown in Figs. 1, 2, and 3 of the drawings no means are provided for positively raising the piercing-point, except the upward pressure and rise of the sheets of the pile under the stress of spring F against it, which will take place as soon as the thrusting-cam K has passed over the end of arm I, thus leaving the arm and the piercing-point free to rise under the action of any sufficient lifting force. It is also observed that when the piercing-point makes its thrusts into the sheets it moves in the arc of a circle and

tends to make the punctures or holes in the upper sheets larger than the piercing-point, and it is further observed that as the upward movement of the sheets provide the only means for raising the piercing-point it will not be lifted out of contact with the upper sheets and is always in position to hold the next lower sheets in place while the upper sheet is started and cut or torn from it.

10 A careful examination and study of the above-described device when in continuous operation upon a full-sized machine for feeding labels and stamps at the rate of over sixty per minute has failed to enable us to state with certainty whether the desired clearance of the piercing-point from fibers is due to the sharp intermittent thrusts of the point into the paper, or to the vibration which the thrusts and the opposing platform-spring give to the pile, or to the circular movement of the piercing-point, or whether the desired result is produced by a combination of these operative conditions. The almost perfect working of this device after several others have been tried and discarded as unsatisfactory shows that the desired clearance is effected and that the point continues to pierce the same number of sheets of equal thickness at each thrust and that the sheets are separated and removed from the pile one by one with regularity and precision.

The operation of the above-described mechanism is as follows: The pile of sheets supported upon the spring-controlled platform is forced up against the starting and feeding rollers and the piercing-point, and as the mechanism is started up the rotating cam K by its contact with the carrying-arm I thrusts the piercing-point downward into the sheets with a positive movement and to a definite distance, determined by the shape of the cam and the arrangement of the connecting parts to pierce the desired number of upper sheets of the pile near their rear ends. As soon as roughened feeding-surfaces of the rotating rollers C and C' come in contact with the top sheet it is started from its place and fed forward toward the drawing-rollers, its rear end being cut or torn away from the piercing-point by its forward movement, while the contiguous sheets are held in place by their contact with the said point. As before stated, it is preferred that the arrangement of the cam K and the surfaces of the feeding-rollers should be so related to each other that the piercing-point will be in its lowest position or home thrust in the sheets when the smooth surfaces are rotating over the sheets, inasmuch as the home thrusts of the point force the sheets away from those surfaces and prevent the starting of the second sheet before the first sheet has been fed forward sufficiently; also that before the roughened feeding-surfaces of the rollers come in contact with the top sheet the piercing-point has been so relieved from the action of the cam that it is free to rise from its lowest position

and permit the pile to be forced up by the expansion of the platform-spring and the upper sheet to be brought into feeding contact with the rollers.

The modification illustrated in Figs. 4 and 5 of the drawings differs in its construction and operation from the device hereinbefore described and shown in Figs. 1, 2, and 3 only in the use of devices to positively raise the piercing-point relatively to the sheets and to limit the upward movement of the pile, and for this purpose a cam-groove X, conveniently formed in the end of roller C, engages with a pin Y, fixed in the free end of arm I, while a stop Z is secured in place at the rear end of the pile slightly above the plane of the bearing of the rollers C C' on the upper sheet. The cam X is shaped to give the piercing-point H the sharp downward thrusts into the sheets, as in the construction hereinbefore described, and in addition thereto to slightly raise it relatively to the sheets when the pile has been moved up by the action of the platform-spring and its rear end has been stopped by its contact against the stop Z.

It is not intended to limit the present invention to the use of starting and feeding rollers or to drawing-rollers or to the special devices for operating the piercing-point or to feeding the sheets from the top of a pile, as described and shown in the drawings, as it is evident that other constructions and forms of devices can be used for these purposes without materially changing the operation of the piercing-point and the advantages resulting therefrom.

What is claimed as new is—

1. In a sheet-separating mechanism, the combination substantially as set forth, of a piercing-point located at the rear of a pile of sheets and means to intermittently thrust the said point into the outer and contiguous sheets of the pile, for the purpose described.

2. In a sheet-separating mechanism, the combination substantially as set forth, of a piercing-point located at the rear of a pile of sheets and means to thrust the point with a circular movement into the outer and contiguous sheets, for the purpose described.

3. In a sheet-feeding mechanism, the combination, substantially as set forth, with devices for starting and feeding the outer sheet of a pile, of a piercing-point located at the rear of the pile and means to intermittently thrust the said point into the outer and contiguous sheets, for the purpose described.

4. In a sheet-feeding mechanism, the combination substantially as set forth, with devices for starting and feeding the outer sheet of a pile, of a piercing-point located at the rear of the pile, devices to intermittently thrust the said point into the outer and contiguous sheets and means operating upon the opposite side of the pile to yieldingly resist the thrust of the point and to force the pile against the same, for the purpose described.

5. In a sheet-feeding mechanism, the com-

bination substantially as set forth, with devices for starting and feeding the outer sheet of a pile, of a piercing-point, as II, a point-carrying arm, as I, pivoted at the rear of the pile, and a rotating cam, as K, whereby the piercing-point is intermittently thrust into the outer and contiguous sheets of the pile for the purpose described.

6. In a sheet-feeding mechanism, the combination substantially as set forth, of a starting and feeding roller, as C, having a section of its cylindrical surface roughened and the rest smooth, a piercing-point located in the rear of the roller and means to thrust the point home into the outer and contiguous sheets when the smooth surface of the roller

is adjacent to the pile, for the purpose described.

7. In a sheet-feeding mechanism, the combination substantially as set forth, of a piercing-point located at the rear of a pile of sheets, a stop, as Z, to limit the movement of the rear end of the pile toward the piercing-point and means to thrust the piercing-point into the outer and contiguous sheets and to give it a relative movement to the sheets in the opposite direction, for the purpose described.
